ELECTROACOUSTICAL APPARATUS

Leslie J. Anderson, Westmont, N. J., assignor to
Radio Corporation of America, a corporation
of Delaware

Application September 30, 1936, Serial No. 103,405

12 Claims. (Cl. 179—1)

This invention relates to electroacoustical apparatus, and more particularly to a microphone of the velocity type such as that disclosed and claimed in the United States patent to Harry F. Olson, No. 1,885,001.

When a velocity microphone of this type is placed close to a small sound source, the low frequency response is considerably accentuated. Since the mouth of a speaker or singer represents a relatively small source of sound, accentuation of low frequencies results when a velocity microphone is employed for close talking. To offset this effect, transformers for such microphones have been designed so that they provide a certain amount of low frequency attenuation. However, when this is done, the resulting pick-up of a plane wave or a near plane wave, such as that obtained from an orchestra, which represents a large sound source, will be lacking in low frequency response. This has necessitated either using two different kinds of microphones where, for example, both orchestral music and voice are being broadcast, one having a flat low frequency response and the other an attenuated low frequency response, or, if but a single microphone is used to pick up sound from both sources, a compromise between the two microphones was necessary with resulting loss in fidelity.

The primary object of my invention is to overcome the foregoing difficulty by the provision of an improved microphone of relatively high sensitivity and the response characteristic of which may be selectively controlled in such a manner as to best suit the particular purpose desired.

More specifically, it is an object of my invention to provide an improved microphone of the type set forth, the low frequency response of which may be readily and easily adjusted to obtain either a flat low frequency response or an attenuated low frequency response, depending upon whether the microphone is to be used to pick up mainly music emanating from a relatively large source and at a relatively great distance therefrom, or whether it is to be used to pick up sound emanating from one's mouth in relatively close proximity thereto.

A further object of my invention is to provide an improved microphone as aforesaid which can be changed to provide one response characteristic or the other without necessity of disassembling the same.

It is also an object of my invention to provide an improved microphone of the type described which is simple in construction, yet highly efficient in use.

In accordance with my invention, I provide a reactor which may be connected, at will, across at least a portion of the secondary of the output transformer of the microphone, the reactance thereof being of such a value that proper attenuation is obtained at the low frequency end when such connection is made. When the reactor is removed from across the transformer secondary, however, the microphone will have a substantially flat response. Preferably, although not necessarily, the reactor and the transformer may be housed in a common shielding case and the reactor connected across the transformer secondary by means of a jumper to which access may be had readily through a small opening in the transformer casing. Suitable indicia, visible through said opening, may be provided to indicate the operating condition of the microphone.

The novel features that I consider characteristic of my invention are set forth with particularity in the appended claims. The invention itself, however, both as to its organization and method of operation, as well as additional objects and advantages thereof, will best be understood from the following description of one embodiment thereof, when read in connection with the accompanying drawings in which—

Figure 1 is a front elevation of my improved microphone with the casing and wind screen removed.

Figure 2 is a circuit diagram showing the connections between the vibratile ribbon and the transformer, and showing, also, the manner of coupling the reactor to the transformer.

Figure 3 is a curve showing the difference in low frequency response of the microphone with the reactor coupled and uncoupled from the transformer, and

Figure 4 is a circuit diagram showing a modification of my invention.

Referring more specifically to the drawings, wherein similar reference characters designate corresponding parts throughout, there is shown, in Fig. 1, a supporting yoke 1 which swivelly carries a pair of mounting pins 3 secured to a U-shaped, preferably non-magnetic but electrically conductive bracket member 5. Secured to the upper ends of the arms 5a and 5b of the bracket 5 are a pair of pole pieces 7 in spaced relation to each other to provide an air gap therebetween in which a conductive element 9, such as a thin, corrugated ribbon of aluminum, is mounted for vibratory movement. The conductive ribbon 9 has its upper end tightly clamped between a pair of blocks 11 and 13, the former of which is of non-

conductive material and the latter of which is of conductive material, the block 11 being secured to the pole pieces 7, as by means of screws 15. The lower end of the conductive ribbon 9 is similarly tightly clamped between a second pair of blocks 11 and 13 through the latter of which extends a pair of set screws 17 locked thereto by the nuts 19. The set screws 17 are threaded into the lower ends of the pole pieces 7 and may be adjustably fixed therein by means of the nuts 21. This construction permits adjusting the tension of the conductive ribbon 9 by manipulating the nuts 19 and the nuts 21 in the manner fully set forth and claimed in my copending application Serial No. 88,174. A pair of magnets 23, one secured to the lower ends of the pole pieces 7 and the other to the upper ends of the pole pieces 7, as by means of bolts 25, serve to supply the necessary flux in the air gap between the pole pieces 7.

Secured to the lower end of the bracket member 5 is a casing 27, preferably made of iron, which houses an output transformer 29. The casing 27 is rectangular in shape and has a cover plate 31 covering the open bottom thereof, the cover plate 31 being provided with an opening 33 for a purpose presently to be set forth. The lower end of the conductive ribbon 9 is connected to one side of the primary winding of the transformer by a lead 35, while the upper end of the conductive ribbon is connected to the arms 5a and 5b of the bracket member 5 by means of a pair of leads 37 and 39, a lead 41 connecting substantially the midpoint 5c of the bracket member 5 with the other side of the primary winding of the transformer 29. This arrangement, which is particularly advantageous in providing a pair of balancing loops which include the ribbon element 9 for eliminating inductive pickup, is fully disclosed and claimed in my copending application Serial No. 77,142, now Patent No. 2,113,364, granted April 5, 1938.

Mounted within the casing member 27 is a terminal board 43 of insulating material to which are fixed a plurality of conductive strips 45, 47, 49, 51, 53 and 55. The transformer 29 is one which may have a frequency response characteristic tending to aid in the reproduction of a preponderance of base frequencies in the transmission of voice signals from the conductive element 9, and is preferably provided with a split secondary winding consisting of the coils 57 and 59. One side of the coil 57 may be connected to the strip 45 and the other side thereof to the strip 49, while the winding 59 may have one side connected to the strip 47 and its other side connected to the strip 51 and, by connecting a jumper or link 61 across the strips 47 and 49, the windings 57 and 59 are connected in series. In accordance with my invention, I provide a compensating reactor 63 for attenuating the base frequencies within the voice range when connected across at least a portion of the secondary winding of the transformer 29, one side of the reactor 63 being connected to the strip 53 and the other side thereof being connected to the strip 51, a lead 65 connecting the strip 47 with the strip 55. A second jumper or link connection 67 is arranged to be connected, at will, across the strips 53 and 55 and, when so connected, couples the reactor 63 across the winding 59 in parallel relation thereto. The reactor 63 is so designed that, when it is connected across the winding 59, it greatly reduces the output impedance of the transformer, thereby greatly at-

tenuating the response at the low frequency end. With the link connection 67 in the open position, however, as shown in Fig. 2, the microphone response will be substantially flat.

Fig. 3 shows a curve of the response of the microphone with the reactor 63 in both positions. The curve designated "Voice" represents the preferred characteristic for a source of sound within the voice or speech range and close to the microphone (for example, about a foot away therefrom), while the curve designated "Music" represents the preferred characteristic for a plane wave field emanating from a large sound source at some distance from the microphone. As will be observed from an examination of Fig. 3, there is a sharp decline at the low frequency end of the curve (designated "Voice") when the jumper 67 is bridged across the strips 53 and 55, in which case the reactor 63 is connected in parallel relation to the winding 59.

The jumper or link connection 67 may be permanently pivotally secured to the strip 53, as by means of a bolt 69. Connection of the jumper 67 to the terminal 55 may be readily effected by means of a screw 71 in the strip 55 which is received in the slot 73 of the jumper 67 when the jumper 67 is moved up into bridging relation, after which the screw 71 may be tightened against the jumper or link 67. The hole 33 is formed to provide easy access to the screw 71 and the jumper 67. The terminal board 43 is preferably marked with the letter M and the jumper 67 with the letter V to indicate the operating condition of the microphone, the letters M and V being readily visible through the opening 33 and representing, respectively, "Music" and "Voice". Thus, the operator can tell at a glance through the opening 33 whether the microphone is set for voice transmission or for music transmission, and by merely inserting a screw driver through the opening 33, the screw 71 can be easily manipulated to permit either removal of the jumper 67 from bridging position to the open position shown in Fig. 2, or vice versa. The output from the microphone may be obtained by means of a cable represented by the leads 75 (Fig. 2) connected to the strips 45 and 51.

Although I have shown and described but one modification of my invention, I am fully aware that many other modifications thereof and changes therein are possible without departing from the spirit thereof. For example, other means than that specifically shown in the accompanying drawings for connecting and disconnecting the reactor 63 across the coil 59 may be employed. Thus, a resistor, either fixed or variable (but shown as a variable resistor 77 in Fig. 4), may be substituted for the jumper 67, in which case varying degrees of attenuation represented by curves falling between the two curves shown in Figure 3 may be obtained. Also, if found desirable, the reactor 63 may be connected across both windings 57 and 59 instead of merely the winding 59. Furthermore, instead of making the opening 33 in the cover plate 31 large enough to provide access to the screw 71 as well as to permit viewing of the letters M and V, the hole 33 may be made small enough to permit only the viewing of the letters M and V, and access to the screw 71 made possible only by the removal of the cover plate 31. This has the advantage of preventing easy tampering with the screw 71 and therefore of perhaps avoiding misadjustment of the operating condition of the microphone by 75

curious or unauthorized persons. Many other changes will, no doubt, readily suggest themselves to those skilled in the art, and I therefore desire that my invention shall not be limited except 5 insofar as is made necessary by the prior art and by the spirit of the appended claims.

I claim as my invention:

1. In sound translating apparatus, the combination of a vibratable element having a predetermined response characteristic tending to accentuate base frequencies when actuated by a small sound source in close proximity thereto, an output transformer having its primary winding connected to said element, a compensating reactor 10 for attenuating said base frequencies, a terminal board, the secondary winding of said transformer and said reactor each having leads connected to said terminal board, and means on said terminal board for connecting said reactor at will across 20 at least a portion of said secondary winding for altering the response characteristic of said apparatus.

2. In a microphone having a predetermined response characteristic for sound energy in the 25 range of speech tending to accentuate base frequencies when the sound source is relatively small and relatively close to the microphone, the combination of a vibratable conducting element mounted for movement in a magnetic field, an 30 output coupling transformer having its primary winding connected to said element, said transformer having a frequency response characteristic tending to aid in reproduction of a preponderance of base frequencies in voice transmission 35 from said element, base frequency attenuating means adapted to cooperate with the secondary winding of said transformer to provide a predetermined desired attenuation of low frequency sounds in the voice range when connected in 40 parallel relation to at least a portion of said secondary winding, a terminal board to which said secondary winding and said attenuating means are connected, and a movable link connection on said terminal board arranged to connect said 45 attenuating means at will in parallel relation to said portion of said secondary winding.

3. The invention set forth in claim 2 characterized by the addition of a casing in which said transformer, said attenuating means and said 50 terminal board are all housed.

4. The invention set forth in claim 2 characterized by the addition of a casing in which said transformer, said attenuating means and said 55 terminal board are all housed, said casing being provided with an opening through which said link connection may be adjusted to connect said attenuating means to and disconnect it from said secondary winding.

5. The invention set forth in claim 2 characterized by the addition of a casing in which said transformer, said attenuating means and said 60 terminal board are all housed, said casing being provided with an opening through which said link connection may be adjusted to connect said attenuating means to and disconnect it from said 65 secondary winding, and characterized further by the addition of means for indicating the position of said link connection.

6. In a microphone having a predetermined response characteristic for sound energy in the range of speech tending to accentuate base frequencies when the sound source is relatively small and relatively close to the microphone and 5 a wider, more general range for music emanating from a relatively large sound source at a relatively great distance therefrom, the combination of a vibratable conducting element mounted for movement in a magnetic field, an output coupling transformer having its primary winding connected to said element, said transformer having a frequency response characteristic which tends to aid in reproduction of a preponderance of base frequencies in voice transmission from 10 said element, a terminal board having terminals connected with the secondary winding of said transformer, additional terminals on said terminal board having a movable link connection for selectively connecting said additional terminals to and disconnecting said additional terminals from each other, and a compensating reactor arranged to be connected across at least a portion of said secondary winding through said 15 terminal board and said additional terminals and 20 link connection.

7. The invention set forth in claim 7 characterized in that said movable link connection consists of a resistor.

8. The invention set forth in claim 7 characterized in that said movable link connection consists of a variable resistor.

9. The invention set forth in claim 7 characterized in that said compensating reactor has a characteristic such that, when said reactor is 35 connected across said secondary winding portion, a predetermined attenuation of base frequencies in the voice range is obtained.

10. The invention set forth in claim 7 characterized in that said secondary winding portion 40 has leads connected with two terminals on said terminal board, and characterized further in that said reactor has one lead connected with one of said terminals and its other lead connected to one of said additional terminals, the other of said 45 additional terminals being connected to the other of said first named terminals.

11. The invention set forth in claim 7 characterized by the addition of a casing in which said transformer, said reactor and said terminal 50 board are all housed, said casing having an opening therein through which access may be had to said link connection for selectively bridging said additional terminals whereby to connect said reactor across said secondary winding portion. 55

12. The invention set forth in claim 7 characterized by the addition of a casing in which said transformer, said reactor and said terminal board are all housed, said casing having an opening therein through which access may be had to said 60 link connection for selectively bridging said additional terminals whereby to connect said reactor across said secondary winding portion, and characterized further by the addition of indicia on said terminal board and said link connection 65 visible through said opening for indicating the operating characteristic of the microphone.

LESLIE J. ANDERSON.

CERTIFICATE OF CORRECTION.

Patent No. 2,183,209.

December 12, 1939.

LESLIE J. ANDERSON.

It is hereby certified that error appears in the printed specification of the above numbered patent requiring correction as follows: Page 3, second column, lines 27, 30, 33, 39, 48 and 56, claims 7, 8, 9, 10, 11 and 12 respectively, for the claim reference numeral "7" read 6; and that the said Letters Patent should be read with this correction therein that the same may conform to the record of the case in the Patent Office.

Signed and sealed this 6th day of February, A. D. 1940.

Henry Van Arsdale,
Acting Commissioner of Patents.
